COMPOSITE SHOE HEEL

Benjamin Gilowitz, New York, N. Y., assignor of
one-fourth to Merris Bousel, New York, N. Y.Application December 10, 1931
Serial No. 580,195

4 Claims. (Cl. 36—35)

In my U. S. Patent 1,821,633 of September 1, 1931, a composite heel is shown in which a body of compressed paper or other relatively cheap inelastic material, is provided in its peripheral edge with vertical grooves, and in which an elastic body underlies said inelastic body and is provided with integral upstanding tongues secured in said grooves. One object of the present invention is to provide a new and improved construction 5 whereby the elastic and inelastic bodies may be more tenaciously secured together.

The patented heel is particularly designed for sport shoes, the visible portions of the elastic and inelastic bodies at the edge of the heel being preferably of contrasting colors, and a further object 15 of the present invention is to provide an improved heel constructed at the factory so that only the elastic material appears at the edge of the heel, it being possible however to buff or grind 20 some of this material away to expose portions of the inelastic body to give substantially the same appearance as in the patented heel, for sport shoes.

With the foregoing and minor objects in view, 25 the invention resides in the novel subject matter hereinafter described and claimed, description being accomplished by reference to the accompanying drawing.

Fig. 1 is a perspective view showing one form 30 of the improved heel.

Fig. 2 is a vertical sectional view on line 2—2 of Fig. 1.

Fig. 3 is a perspective view showing a different 35 form of construction.

Fig. 4 is a vertical sectional view on line 4—4 of Fig. 3.

Fig. 5 is a perspective view showing a still 40 further form of construction.

Fig. 6 is a detail vertical sectional view on line 4—6 of Fig. 5.

Fig. 7 is a perspective view showing yet another 45 form of the invention.

In Figs. 1 and 2, the numeral 8 denotes an inelastic body whose upper side is concave to properly fit the heel portion of a shoe. This concave formation may well be imparted to the body by pressing the latter into concavo-convex form in 50 vertical section, as shown. The body 8 is formed with a plurality of relatively wide dove-tail 55 grooves 9 in its peripheral edge, all of said grooves opening through both the upper and lower sides of said body. Near the front corners of this body, additional relatively narrow dove-tail grooves 10 are formed in the inner walls of the foremost 55 grooves 9. The body 8 is also preferably formed

with a central opening 11 which may be of circular outline or other desired shape.

An elastic body 12 underlies and is secured against the inelastic body 8, said elastic body being provided with an integral central portion 13 60 molded in the opening 11 and with upstanding dove-tail portions 14 molded in the grooves 9. The inner sides of two of the portions 14 are provided with integral dove-tail portions 15 molded in the relatively narrow grooves 10. 65

By the construction shown and described, a heel is provided in which there is an unusually tenacious connection between the inelastic and the elastic bodies, said heel being intended primarily for sport shoes, in which case, the two 70 bodies 8 and 12 will be of different colors to present a pleasing appearance at the edge of the heel.

In Figs. 3 and 4, the inelastic body 8^a is substantially identical with the body 8. The elastic body 12^a however, is provided with a continuous 75 upstanding rim flange 16 which surrounds and is molded against the peripheral edge of the body 8^a. The inner side of the flange 16 is provided with integral dove-tail portions 14^a molded 80 in the dove-tail grooves 9^a, and the inner sides of two of said portions 14^a are provided with relatively narrow dove-tail portions 15^a molded in the relatively narrow dove-tail grooves 10^a. 85

The flange 16 obscures the peripheral edge 85 of the body 8^a so that the heel is well adapted for ordinary instead of sport shoes. However, by buffing, grinding or otherwise removing the flange 16, the peripheral edge of the inelastic body 8^a is made visible between the grooves 9^a 90 and hence the same effect as in Fig. 1, is obtained, for sport shoes.

Metal staples 17 are driven through the body 8^a and their legs are embedded in the elastic body 12^a, said legs being preferably roughened 95 as denoted at 18. These staples 17 thus perform the function of providing additional connecting means between the two bodies 8^a and 12^a.

In Figs. 5 and 6, the construction is practically identical with that shown in Figs. 3 and 4, the 100 only difference being in the number of the dove-tail grooves and elastic portions 9^b and 14^b, and in the use of nails 17^a instead of the staples 17. The nails 17^a which have been shown, are provided with large heads and roughened bodies, 105 but other suitable fastening means could be used instead.

In Fig. 7, all of the dove-tail grooves 9^c in the body 8^c, with one exception, are provided in 110 their inner walls with relatively narrow dove-

tail grooves 10°, and the elastic body 12° is provided with relatively wide dove-tail portions 14° molded in the grooves 9°, and with comparatively narrow dove-tail portions 16° molded in the 5 grooves 10°. This construction establishes an unusually tenacious connection between the elastic and inelastic bodies of the heel and while shown in a heel for sport shoes, could also be employed in a heel for ordinary shoes, such as 10 shown in Figs. 3 and 5.

While the various grooves have been described as dove-tail grooves, attention is invited to the fact that each of these grooves is provided with opposed vertical side walls which converge to 15 toward the peripheral edge of the heel instead of converging upwardly, as would be the case with dove-tail grooves or recesses of conventional form.

Excellent results are obtainable from the details disclosed and they are therefore preferably followed. However, within the scope of the invention as claimed, variations may be made.

I claim:—

1. A composite heel comprising an inelastic body having relatively wide grooves in its peripheral edge, each of said relatively wide grooves having opposed vertical side walls which converge toward said peripheral edge of said inelastic body, a plurality of said relatively wide grooves having relatively narrow grooves in their inner walls, each of said relatively narrow grooves also having opposed vertical side walls which converge toward said peripheral edge of said inelastic body, and an elastic body upon which said inelastic body is secured, said elastic body having integral upstanding portions secured in and filling said grooves.

2. A composite heel comprising an inelastic body having grooves in its peripheral edge, said

40

grooves opening through the upper and lower sides of said inelastic body, and an elastic body to the upper side of which said inelastic body is secured, said elastic body having an integral upwardly projecting flange lying against and secured to said peripheral edge of said inelastic body, the inner side of said flange being provided with integral portions secured in said grooves.

3. A composite heel comprising an inelastic body having grooves in its peripheral edge, said grooves opening through the upper and lower sides of said inelastic body and each having opposed vertical side walls converging toward said peripheral edge of said inelastic body, and an elastic body to the upper side of which said inelastic body is secured, said elastic body having an integral upstanding flange lying against and secured to said peripheral edge of said inelastic body, the inner side of said flange being provided with integral portions secured in and filling said grooves.

4. A composite heel comprising an upper body of one color having vertical grooves in its peripheral edge opening through both the upper 100 and lower sides of said upper body, a lower body of another color having attaching portions projecting upwardly from the upper side of said lower body and secured in said grooves, and means forming the peripheral edge of the complete heel from heel seat to tread and normally obscuring said peripheral edge of said upper body and said attaching portions, providing a heel for ordinary shoes, said obscuring means being readily removable to expose the different colors 110 of said upper body and said attaching portions when the heel is to be used for sport shoes.
